Attorney*

UNITED STATES PATENT OFFICE.

RAYMOND C. PATTON, OF NELSONVILLE, OHIO.

DOOR-LOCK.

1,357,112.

Specification of Letters Patent. Patented Oct. 26, 1920.

Application filed September 5, 1919. Serial No. 321,795.

To all whom it may concern:

Be it known that I, RAYMOND C. PATTON, a citizen of the United States of America, residing at Nelsonville, in the county of 5 Athens and State of Ohio, have invented new and useful Improvements in Door-Locks, of which the following is a specification.

The object of the invention is to provide a supplemental door lock adapted for manipulation only from the inside of a building or apartment, the same being in the nature of a bolt designed to supplement the ordinary locking means for additional security; and in this connection to provide a 15 device for the purpose indicated which can be readily applied to a door without detracting objectionably from the appearance thereof while affording means for holding the door closed even in the event that the 20 ordinary locking device should be forced or manipulated from the outside of the door.

To this end the invention consists in a construction and combination of parts of 25 which a preferred embodiment is shown in the drawing, it being understood that changes in form and proportion may be resorted to, within the scope of the claim without departing from the principles involved.

In the drawing:

Figure 1 is a front inside view of a door fitted with a locking device embodying the invention.

35 Fig. 2 is a detail view partly broken away of the bolt operating means.

Fig. 3 is a longitudinal sectional view of the device.

Fig. 4 is a transverse sectional view on 40 the line 4—4 of Fig. 2.

Fig. 5 is a detail view of the joint between relatively adjustable elements of one of the bolt members.

Essentially the device consists of bolt 45 members 10 extended near their remote ends through guides 11 secured as shown, to the door 12 or other closure to be locked, and terminally engageable with sockets 13 formed in the frame or casing of the closure, the inner or adjacent ends of said bolt members being pivotally connected with a disk 14 revolvably mounted upon a spindle 15 supported by a base plate 16 attached to the door or closure. Said disk is preferably provided with a grip or hand hold 17

to facilitate the turning thereof, and carried by the disk is a lock casing 18 having a bolt 19 for engagement with a hasp 20 secured to the base plate. The construction of the lock mechanism may be varied obviously and may involve the necessity of using a key for the release of the disk, in which event a tumbler 21 having a suitable keyhole 22, may be employed. In any event, however, the disk is provided with a locking means for securing it in a fixed relation with the base plate to prevent revoluble movement with the consequent operation of the bolt members, so that a separate operation is necessary in order to release the disk 70 to permit of the disengagement of the bolt members from the sockets in the door frame or casing.

When the disk is turned to extend the bolt members into engagement with said 75 sockets it is locked against reverse movement by the engagement of the bolt 19 with a seat provided for its reception in the hasp, and the reverse movement necessary to disengage the remote extremities of the bolt 80 members from said sockets necessitates the manipulation of the lock to withdraw the bolt 19 from engagement with the seat which in effect is formed in or constitutes a part of the stationary base plate. 85

It will be understood that by arranging this device with the bolt members in substantial alinement vertically in a plane intermediate between the free and hinged edges of the door but preferably nearer to the free edge but set back from the ordinary lock mechanism 23, the forcible opening of the door even in the event that the ordinary lock mechanism should be released or broken will be effectually prevented, whereas when 90 the auxiliary locking device is not needed, its location on the door will not interfere in any way with the usual manipulation thereof, through the means ordinarily provided for that purpose. 95

In order to provide for an adaptation of the locking mechanism to doors or closures of different dimensions each of the bolt members is preferably made extensible or variable in length, as by providing one of 105 the elements thereof with a longitudinal slot 24 for the reception of a polygonal block 25 on the other element, and securing said elements in the desired relative positions to insure the seating of the terminals 110

thereof in the sockets formed in the frame or casing, by means of bolts 26 or equivalent fastening devices.

Furthermore in order to strengthen the joint between the inner ends of the bolt members and the operating disk, the latter may be provided with rounded seats 27 for the reception of the rounded ends of said members, the curvature of the terminals 10 being concentric with the pivots by which connection is made between the bolt members and the disk as shown clearly in Fig. 2.

What is claimed is:

A device of the class described, having

bolt members and means for actuating the same for engaging the remote terminals thereof with sockets in the frame of a closure, said means comprising a revoluble disk with which the bolt members have terminally pivoted connections, the disk being 20 formed with rounded seats and the bolt members being formed with rounded terminals, said terminals and seats being concentric with the pivoted connections for the purpose specified.

In testimony whereof I affix my signature.

RAYMOND C. PATTON.
